UNITED STATES PATENT OFFICE.

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FEELER FOR LOOMS.

Application filed December 28, 1927. Serial No. 243,060.

This invention relates to improvements in weft replenishing looms and it is the principal object of the invention to provide a readily assembled detector wherein the several parts 5 are quickly disconnected from each other.

In the usual multi-color weft replenishing loom the actuating lever which controls the operation of the magazine has a periodic movement which is interrupted at the time 10 of indication of weft exhaustion to initiate replenishment. The interruption is brought about by a controller pin which as ordinarily constructed is separate from the detector mechanism. The actuator lever and its controller pin always occupy the same relative position with respect to the magazine but the detector is subject to adjustment longitudinally of the shuttle depending upon the styles of bobbins and length of shuttles used. It is an 15 important object of my present invention to make the controller pin readily detachable from the detector mechanism without requiring the use of tools so that by a mere hand operation the weaver or loom fixer may adjust 20 the controller pin to correspond with the varying positions of the detector mechanism.

It is a further object of my invention to provide a quickly detachable cover which can 25 be clamped to the detector without the use 30 of screws or bolts or other attaching means, the cover being held in place by friction and being slipped off the detector readily to permit inspection or adjustment of the detector parts. It is a further object of my invention 35 to provide an improved form of weft detector element formed of sheet metal and having bearing and detecting surfaces of increased thickness.

With these and other objects in view which 40 will appear as the description proceeds, my invention resides in the combination and arrangement of parts hereinafter described and set forth in the claims.

In the accompanying drawings, wherein I 45 have shown a convenient embodiment of my invention,

Fig. 1 is a plan view of my improved detector showing the same moved forwardly to non-indicating position by a sufficient supply of weft, the cover being in section to illustrate the working parts of the detector,

Fig. 2 is a partial front elevation of the detector looking in the direction of arrow 2, Fig. 1,

Fig. 3 is an enlarged vertical section on line 55 3-3 of Fig. 1,

Fig. 4 is a side elevation on an enlarged scale of the detector element looking in the direction of arrow 4, Fig. 1,

Fig. 5 is a fragmentary enlarged vertical 60 section taken on line 5-5 of Fig. 1 to illustrate the manner of mounting the removable controller pin,

Fig. 6 is a view similar to Fig. 1 but with the detector moved to indicating position 65 while in contact with an insufficient supply of weft,

Fig. 7 is a detailed sectional view taken in the direction of arrow 7, Fig. 5 showing a portion of the removable controller pin, and 70

Fig. 8 is a perspective view showing the method of removing the controller pin.

Referring to the drawings I have shown a feeler stand 10 and a guide 11 both of which are fixed, said guide having a slot 12 extending substantially parallel to the shuttle S to receive an actuator lever 13 mounted for vertical reciprocation in said slot. The inner or left end of said lever is connected to the replenishing mechanism not shown and is 80 effective to initiate replenishment when the detector indicates substantial exhaustion of weft. The device for determining the operation of the actuator lever includes a control member 14 having an end which normally 85 lies in the path of the actuator lever but is withdrawn from such path when sufficient supply of weft is present on a detecting beat. The matter thus far described with the exception of the particular form of the control 90 member 14 is of common construction and for a further description and understanding of the same reference may be had to patent to Ryon No. 1,030,748.

In carrying my improvements into effect 95 I provide a feeler base 20 having a depending foot 21 which may be secured to the stand 20 by means of bolt 22 extending through mutually perpendicular slots 23 formed in the stand and foot to permit vertical and horizontal adjustment of said base 20 with respect to the stand 10. The base has a floor 24 from which extends upwardly longitudinal walls 25 and rear and forward transverse walls 26 and 27, respectively.

A sliding carrier 30 is provided with vertical longitudinal walls 31 which lie inside the adjacent walls 25 of the base and are

guided by said walls 25 to require the carrier to move forwardly in a line substantially perpendicular to the shuttle S. Said slide is provided at the rear end thereof with an 5 upstanding stud 32 and a stop 33 struck up from the bottom of the carrier. The left side of said sliding carrier as viewed in Figs. 1 and 6 is provided with a plurality of guide ears three of which are shown in the drawings. The rear ear 34 extends upwardly 10 from the bottom of the carrier and is bent to the right defining a U-shaped guide which is open on the right hand side thereof. Guide 35 is formed similarly to guide 34 but is located at the forward end of the sliding carrier. The intermediate guide 36, however, opens at the left as indicated in Figs. 5 and 8. The carrier is so proportioned that the 15 rear end thereof normally lies against the back transverse wall 26.

The detecting element 40 as shown more particularly in Figs. 1, 4 and 6 comprises a single piece of sheet metal the rear end of which may be bent back on itself as at 41 to 20 provide a portion of double thickness across which vertical yarn engaging teeth 42 extend. The forward end of said detector has a second portion 43 bent back on itself to provide a bearing of double thickness for 25 the stud 32. A forwardly extending tail 44 is positioned for engaging with the stop 33 when the detector is in normal position. Any 30 convenient means as a cotter pin 33' may be employed to restrain relative vertical movement of the detector and sliding carrier. Said detector is provided with a transverse flange 45 through which extends a plurality 35 of perforations 46 and the detector is so made that the flange 45 and the teeth 42 lie to one 40 side of the longitudinal axis of the detector with respect to the stud 32.

A single yielding means is provided to hold the parts in proper position, said means including a rod 50 the rear end of which extends through one or another of the perforations 46 and the forward end of which is provided with a crimp 51 and is then extended through an opening 52 in the forward wall 27. A compression spring 53 surrounds the 50 rod 50 and lies between the crimp 51 and the flange 45, said spring serving to hold the parts in rear position with the rear end of the sliding carrier against the transverse rear wall 26 and with the tail 44 against the stop 33 to properly position the detector 40. The pressure exerted by the spring 53 and tending 55 to resist angular movement of the detector member 4 may be varied by locating the rod 50 in one or another of the perforations 46, the greater resistance to turning occurring when the rod is farthest from the axis of the detecting member.

The control member 14 a portion of which has already been described includes a transversely extended portion 60 which may be op-

erated upon at the time of transfer to be moved forwardly by mechanism well understood but not shown and said controller may have a rearwardly extending portion 61 which as illustrated in Figs. 5 and 7 is provided with an offset 62 located between the guides 35 and 36, the purpose of the offset being to prevent back and forth movement of the control member relatively to the sliding carrier and said offset extending vertically 75 as shown in Fig. 5 when the controller is in normal position. In this way the controller is held against displacement with respect to the sliding carrier under normal operating conditions of the detector. The rear end of 80 the portion 61 may extend through the rear guide 34 to hold said control member more firmly in place.

In order to provide means for restraining upward movement of the sliding carrier and 85 the detector with respect to the base 20 and also to prevent the accumulation of lint and dirt in the operating parts of the detector I provide a cover 70 having a top 71 from the edges of which depend flanges 72. The 90 space between the inner edges of said flanges is normally slightly less than the distance between the outsides of the walls 25 and said cover is made of pressed metal or other slightly resilient material so that the flanges 72 95 will be held frictionally against the walls 25. As viewed in Figs. 1 and 6 the right hand flange 72 may be shorter than the opposite flange to provide room for the swinging of the detector members 40 should the latter 100 receive an excessive movement from any accidental cause, such as a misplaced bobbin.

Under normal conditions with the detector parts in their rearmost position the full supply of weft on bobbin B will engage the 105 teeth 44 and move said detector forwardly so that the sliding carrier will assume the position shown in Fig. 1 with respect to the base 20. Because of the guide 36 control member 14 will be moved forwardly under these conditions and the actuator lever 13 will descend without interruption. When insufficient weft remains, however, the detector will slide along the bobbin B to the position indicated in Fig. 6, the sliding carrier remaining at 110 rest because of the fact that the pressure of the compression spring 53 is applied to the detector at a point between the stud 32 and the teeth 42 with respect to the length of the bobbin. The control member 14 will therefore 115 remain under the actuator lever to interrupt the downward movement of the latter and initiate weft replenishment.

When it is desired to adjust the distance between the controller 14 which cooperates 120 with the actuator lever 13 and the portion 61, the cover will be removed and the slide moved forwardly a sufficient distance to withdraw the controller end 14 from the stand 12, after which said controller may be turned 125 130

in a clockwise direction as indicated by the arrow C in Fig. 2 until the offset 62 lies flat against the bottom of the sliding carrier. In this position the offset can be slid forward-
ly through the opening of guide 35, the rear part of the portion 61 sliding forwardly between the slides 34 and 36. After the controller has been given its proper setting it can be inserted by an operation the reverse
of that necessary for its removal. If it be desired to guard against accidental displacement of the controller pin from the stand 12 by having the controller pin extending into said stand when the sliding carrier is in its foremost position on the base, the carrier may be removed bodily from the base, there being no restraining screws, lugs or other projections extending from the base into the path of removal of the sliding carrier.

From the foregoing it will be seen that I have provided a weft detector wherein the several parts thereof may be readily disassembled so that adjustments may be made without requiring tools or other devices to take apart the several elements of the detector. It will further be seen that the controller member can be quickly removed from the sliding carrier by a partial rotation so that the offset part of the controller will pass through the open guide 35. It will also be seen that the cover 70 which is frictionally held in position can be quickly removed but when in position serves to restrain upward movement of the sliding carrier and the detector. Furthermore, the detector is made of sheet stock one portion thereof bent back on itself to afford increased thickness and that said detector can have operative contact with the compression spring 53 at a plurality of distances from the axis of said detector.

The controller in the type of weft detector as set forth herein is normally in the path of the actuator and this sometimes causes slight annoyance when turning the loom over by hand with an empty shuttle as might be the case when starting up the warp for a new loom. Under these conditions there would be no agency acting to move the controller out of the path of the actuator and as a result every other pick of the loom would cause a downward movement of the transerrer arm and a releasing of bobbins should the magazine be supplied with the latter. The cover as set forth herein can be moved so that the vertical wall adjacent the actuator can be placed to hold the controller forwardly of the path of movement of the actuator so that the loom may be turned over by hand without the objectionable repeated operations of the magazine.

Having thus described my invention it will be apparent that changes and modifications may be made therein by those skilled in the art without departing from the spirit and

scope of the invention and I do not wish to be limited to the details herein disclosed, but what I claim is:

1. In weft detecting mechanism for looms, a support, a carrier slidable on the support, 70 a regularly moving actuator effective to cause a change in the loom when movement thereof is prevented, a detecting element to engage the yarn mounted on the carrier, and a controller normally in the path of the actuator and withdrawn when sufficient weft is present, said carrier and controller being held together by detachable means which are releasable only after an angular movement on the part of the controller relatively to the 80 carrier.

2. In weft detecting mechanism for looms, a sliding carrier, a regularly moving actuator effective to cause a change in the loom when movement thereof is interrupted, a weft de- 85 tecting element mounted on the carrier to cause forward movement of the latter when sufficient weft is present, a controller for the actuator normally in position to interrupt movement of the actuator but movable from 90 such a position when sufficient weft is present, and detachable interengaging connections between the carrier and the controller to cause said controller to move with the carrier, said controller and carrier being sep- 95 arable from each other only after an angular movement of the controller relatively to the carrier.

3. In weft detecting mechanism for looms, a sliding carrier, a yarn engaging detecting 100 element mounted on the carrier to cause forward movement of the latter when sufficient weft is present, an actuator element having a regular movement on detecting beats of the loom and effective to cause a change in the 105 operation of the loom when said regular movement is interrupted, a controller member normally connected to and moving with the carrier and normally positioned to interrupt the regular movement of the actuator, 110 and releasable interengaging connections between the controller and the carrier, said controller and carrier being separated only after an angular movement of the controller relatively to the carrier.

4. In weft detecting mechanism for looms, a sliding carrier member, a detecting element mounted on the carrier member to cause forward movement of the latter when sufficient weft is present, an actuator having a regular 120 movement on detecting beats of the loom and effective when said regular movement is interrupted to cause a change in the operation of the loom, and a controller member detachably connected to the carrier member and having a portion normally in the path of the actuator, said members being releasable from each other only after relative angular movements thereof.

5. In weft detecting mechanism for looms, 130

an actuator having a regular movement on detecting beats of the loom and effective when such movement is interrupted to cause a change in the operation of the loom, a detecting element, a carrier on which the element is mounted, said detector and carrier moving forwardly on detecting beats of the loom when sufficient weft is present, a controller normally positioned to interrupt the downward movement of the actuator, guide means formed on the carrier to receive a portion of the controller, an open bearing formed on the carrier to receive other portions of the controller, and a projection extending laterally from the controller located between the guide means and open bearing and tending to prevent longitudinal movement of the carrier and controller, said controller being movable angularly relatively to the carrier so that the projection may be withdrawn through the open bearing.

6. In weft detecting mechanism for looms, an actuator having a regular movement on detecting beats of the loom and effective when such movement is interrupted to cause a change in the operation of the loom, a detecting element, a carrier on which the element is mounted, said detector and carrier moving forwardly on detecting beats of the loom when sufficient weft is present, a controller normally positioned to interrupt the downward movement of the actuator, said controller having a rearwardly extending portion operatively related to the carrier, a guide on the carrier to receive the rear end of said portion of the controller, a forward open bearing on the carrier for the said portion of the controller, and a laterally extending projection formed on the controller normally to engage the open bearing and guide to prevent longitudinal movement of the controller.

troller relatively to the carrier, said controller being removable from the carrier only after the projection has been so placed that it may be withdrawn through the open bearing of the carrier, whereby said controller may be disconnected from the carrier.

7. In weft detecting mechanism for looms, a fixed stand, a carrier slidably mounted on the stand, a yarn engaging weft detecting element pivotally mounted on the carrier, a regularly moving actuator member, a controller for the member operatively connected to the detecting element and normally in the path of the actuator member, means defining up-standing walls on the stand, corresponding walls formed on the carrier to engage the first named walls to prevent relative lateral movement of the stand and carrier in the direction of the length of the surface to be detected, a cover extending over the carrier and frictionally engaging the walls of the stand and positioned to prevent upward movement of the walls of the carrier, said cover being movable in frictional engagement with the walls of the stand to a position to engage and hold the controller out of the path of the actuator.

8. In a weft detecting mechanism for looms, an actuating member, a control member to be engaged by the actuating member to initiate a change in the operation of the loom, a yarn engaging weft detector operatively connected with the control member, means including a cover to define a housing for the yarn engaging member, said cover capable of assuming a position to hold the control member out of operative relation with the actuating member.

In testimony whereof I have hereunto affixed my signature.

RICHARD G. TURNER.
